ABSTRACT OF THE DISCLOSURE

My device is a gauge wherein an electric circuit is broken by objects of a minimum size. Conversely, objects having a portion too small for use will not break the circuit. Light signals in the circuit indicate the acceptability of the objects.

BACKGROUND OF THE INVENTION

My invention may be used on various objects. Use for compressor blades is very practical although its use is not limited thereto.

As is well known in the art, compressor blades, such as those used on turbines and jet engines, frequently require reconditioning. While in use blades are often struck by foreign particles. Also, erosion takes its toll. Reworking defective blades restores usability to some. Because such reconditioning reduces the width of a portion of the blade, it is desirable to simply and easily determine if the blade is then within acceptable tolerances.

Existing methods of checking the reworked blades include the use of micrometers or indicators. Such manual operations do not involve a check of the complete profile of the blade. If only the portions checked have acceptable dimensions, blades with reworked but unchecked undersize portions may erroneously be accepted as good. Also, a relatively large amount of time is taken in transferring the reworked blade from check point to check point. There is exposure to mistakes in judgment on acceptability of blades with loss of material, time and safety.

SUMMARY

My invention avoids the shortcomings of the existing art. Even by unskilled persons, the complete profiles of objects may now be checked simply, accurately and quickly. Two parallel rows of metallic, movable fingers are an important feature of my invention. The rows are at a specified distance apart. The space between the rows is slightly less than the minimum width of the objects to be checked.

Dual electrical circuits are formed to include the following: two parallel insulated bar conductors which movable portions of the fingers uniformly abut; two conducting members each of which is in fixed contact with the respective rows of fingers; an electrical energy source connected thereto; dual light signals wired in series in each circuit and appropriate off-on switches.

When an object to be checked is placed between the rows of fingers any portion thereof that might be too narrow for use will fail to force one or more fingers away from the bar. At least one finger contacting the bar results in an unbroken electric circuit, indicated by the lighted signal. The operator thusly has sufficient information to reject the inadequate object.

BRIEF DESCRIPTION OF THE DRAWINGS

In the drawings showing preferred embodiments of my invention wherein like numerals indicate like parts throughout,

2

FIGURE 1 is a perspective view of my complete device with a few fingers removed from the middle of one row thereof.

FIGURE 2 is a perspective view of one finger.

FIGURE 3 is a cross-sectional view of a portion of one end of the device.

FIGURE 4 is a cross-sectional detail showing the position of the fingers when not in use.

FIGURE 5 is a cross-sectional detail showing the position the fingers may take when an object is being checked.

FIGURE 6 is a detail of the object holder aligned with object to be inserted.

FIGURE 7 is a detail thereof in position for testing an object.

FIGURE 8 is a top view of the holding block without presence of an object to be checked.

FIGURE 9 is same as that of FIGURE 8 with the presence of an object that checks "good."

FIGURE 10 is like that of FIGURE 9 except an object that checks "bad" is present.

DESCRIPTION OF PREFERRED EMBODIMENT

Referring to the drawings forming a part hereof, the numeral 1 of FIGURE 1 indicates a mounting plate with support block 9 integral therewith. Block 9 may be formed of any suitable non-conductive material. It preferably has the same surface contour as an object to be checked. That illustrated is of a compressor blade. The block functions as a master guide for aligning articles to be checked.

Articles to be tested thereon are held in retainer 7. For compressor blades 27 slot 28 accepts the shoulders 29 thereof to stop 32. When a blade is slideably mounted in direction of the arrow of FIGURE 6, it is held in place by screw 30.

Extended portion 31 of retainer 7 is pivotably mounted with a pin in projections 33 of FIGURE 7. Objects may then be swung out of contact with block 9 when being replaced.

Changes may result in the longitudinal center line of objects, such as blades, if one side is reworked more than another. Within centering portion 8, mounted on plate 1, I have provided a common rack and gear (not illustrated). By turning of knob 38 (FIGURE 9) the operator may move the object in direction of arrows. Desired centering of the object 27 on block 9 may quickly and easily result. Duplicate adjustable stops may define the extent of movement as spaces 36 and 37 are occupied.

Secured to block 9 is electrical conducting bar 12. Bar 12 is insulated from block 9 which is a non-conductor. Recessed pins 10 may hold the bar onto the block. This bar has the length and shape of the edge of the object to be checked. For blades a duplicate bar 17 is also mounted on the block parallel to bar 12.

Each bar is connected to ordinary signals such as lights 2 and 3 mounted on plate 1. Wires 18 and their counterparts 19 may carry electrical current through orifice 22 of the plate from bars 12 and 17 to the respective signals. A conventional electrical power source (not illustrated) well known to skilled technicians may energize the system. One or more conventional off-on switches 4 and 5 may be hooked into the circuit in series. Various arrangements may be made. I prefer one switch 4 for connecting the bars and lights with another switch 5 connected to the system for by-passing the hereinafter described circuit components. Testing the lights and system can result with switch 5.

A further important component of the circuitry are a plurality of novel fingers 11, best seen in FIGURE 2.

They serve as electrical conductors and are made of metal of spring temper. A relatively narrow, thin, shaft 15 provides the needed elasticity. A straight edge base of the flattened head is formed at right angles to shaft 15. This facilitates critical operative mounting on flat surface 13 of block 9, see FIGURE 1. These fingers are the link between the profile of the object checked and the signal. They include the irregularities of certain machined parts to detection in the eye of the operator. As such they are arranged, preferably about sixteen per inch, along the path to be occupied by the edge of the object tested. Their closeness to each other determines the number of check points. I prefer the fingers sufficiently close to touch one another on both sides. In the case of blades, as illustrated, the fingers are in two parallel straight rows 6, see FIGURE 8. While under slight tension all fingers touch a described conducting bar at points 25 and 26. There is sufficient force to permit a flow of current under low voltage. The tension is weak enough, however to permit objects to force the fingers away from the bar with slight friction. This action is shown in FIGURE 5, exaggerated for purposes of illustration. In actual use the blade would be centered.

Finally one or more finger retaining bars 14 is provided to hold the end of the shaft of all fingers permanently against the block 9. Also, being made of conducting metal, it completes the electric circuit for it is wired in series, to the aforementioned components. For blade checking I use two parallel bars 14 to hold the two rows of fingers. FIGURE 3 shows the connections of wires 20 and 21 with usual threaded nuts 23 on threaded studs of the bars.

In operation an acceptable blade, having broader width than the space between the bars 12 and 17, pushes all the fingers out of contact with the bars, thusly breaking the circuit, as evidenced by a light signal going off. It is shown in FIGURE 9. On the other hand, a defective blade, with unacceptable recesses 39 permits undisturbed contact between blade and bar in the area of the recess. At least one finger thereby maintains the circuit, illuminating the signal.

It is to be understood that those skilled in the art may make routine modifications hereof which will fall within the scope of my described invention.

I claim:

- 5 1. In an electric gauge the combination of:
  - (a) a mounting block,
  - (b) a supporting block integral therewith,
  - (c) a plurality of movable fingers aligned in two oppositely disposed straight parallel rows along each side of the block,
  - (d) dual conducting bars positioned on the support block, each of which is electrically engageable by all the fingers in the row nearest thereto,
  - (e) dual retaining bars each of which is always in electrical contact with all the fingers of one of the rows,
  - (f) electrically activated signal means connected in series with the retaining bar and conducting bar,
  - (g) means for retaining a blade to be gauged between the rows of fingers,
  - (h) means for laterally adjusting the position of the blade in respect to the rows of fingers.

20 2. The claim according to claim 1 wherein the signal means is a light bulb.

3. The claim according to claim 1 wherein the means for retaining a blade is provided with adjustable screw means for securing the blade within a swivelly mounted holder.

4. The claim according to claim 1 wherein the means for laterally adjusting the position of the blade consists of a manually rotatable knob operatively connected to the means for retaining a blade.
